UNITED STATES PATENT OFFICE.

RICHARD E. BAUS, OF DETROIT, MICHIGAN, ASSIGNOR TO THE STUDEBAKER CORPORATION, OF DETROIT, MICHIGAN, A CORPORATION OF NEW JERSEY.

SHIPPING DEVICE.

Application filed June 14, 1924. Serial No. 720,102.

This invention relates to means for holding boxes during shipment so as to prevent undue movement of the same, and has for its principal object the provision of such means that will be simple and effective, and that will reduce the time of loading and unloading such boxes.

Another object is to provide means whereby such boxes will be held in place without any spikes or nails being driven into the boxes for that purpose, thus eliminating possible injury to the contents of the box from that cause.

Another object is to provide such means that will be light in weight without sacrificing strength and efficiency, and thereby reduce the cost and dunnage charges on the article shipped.

A further object is to provide anti-skid plates between the boxes and the floor, or between a box and one directly above it in cases where the boxes are superimposed during shipment.

A still further object is to provide load clamps for such boxes to hold them down on the floor, of such a nature that any shifting of position of the boxes automatically acts to increase the resistance to further movement of the same.

In the shipping of large boxes by railroads, particularly crated automobiles on flat cars, great difficulty has been experienced in preventing them from breaking loose from their fastenings when the cars are subjected to violent shocks such as are often experienced in switching. For this reason it has been the custom of shippers to secure the boxes together by running boards, planks or the like between and across the boxes and nailing them to the same, and nailing or spiking the lower boxes directly to the car floor. This method, although usually sufficient to hold the boxes on the cars, is such that a severe jar or shock is likely to move or shift the boxes, causing the nails or spikes to pull out or to tear the boxes where they are nailed and freeing the boxes from their fastenings.

The labor involved in so securing the boxes on the cars and in removing them from the same is considerable, and inasmuch as the laborers engaged in unloading such boxes are notoriously disregardful of the manner in which they unload the boxes, or mutilate them, the

dunnage resulting from removing the securing members by crow-bars and the like is very often of great consequence. Another objection to the conventional method of securing such boxes is that it necessitates the use of considerable lumber which is generally a total loss after shipment and which, of course, increases the dunnage charges.

The objects of the present invention, as stated above, are to provide a means for shipping such boxes whereby the objections to the conventional method are overcome.

The above being among the objects of the present invention, the same consists of certain features of construction and methods of application and use, to be hereinafter described with reference to the accompanying drawings, and then claimed, having the above and other objects in view.

In the accompanying drawings, which illustrate suitable embodiments of the present invention and in which like numerals refer to like parts throughout the several views:

Figure 1 is a perspective view which illustrates the adaptation of the present invention to a shipment of three boxes on a flat car, the car floor only being shown and part of the boxes being broken away to better show the application of the anti-skid plates thereto.

Figure 2 is an end view of the load illustrated in perspective in Figure 1.

Figure 3 is a perspective view of one of the anti-skid plates.

Figure 4 is a perspective enlarged view of a fragment of the anti-skid plate shown in Figure 3, illustrating the manner in which it is formed.

Figure 5 is an enlarged view of a fragment of one of the boxes, showing a preferable manner of application of the anti-skid plate thereto.

Figure 6 is an elevational view showing a preferred form of shipping boxes where one is directly superimposed over another.

Although it is to be understood that this invention is applicable to the shipment of large boxes or crates of any type, for the purpose of illustration I have shown boxes in which may be presumed to be automobiles, inasmuch as these are relatively large and heavy and must be handled with a certain amount of care, and as has been explained,

a great amount of difficulty has been experienced in shipping the same when the conventional securing means has been employed.

In Figures 1 and 2 is shown a floor 10 5 (which for the purpose of illustration may be presumed to be the floor of a flat car, although it is to be understood that this invention is applicable to the shipment of boxes on the floor of any suitable carrier) upon 10 which are supported three boxes 11, 12 and 13, the boxes 11 and 12 being positioned end to end directly on the floor 10 but having the ends somewhat separated, and the box 13 is positioned above and resting substantially 15 in equal amounts on the boxes 11 and 12.

The boxes are usually constructed, and it is preferable to have them constructed, with skids 14 on their bottoms. These skids 14 are merely boards or planks running the 20 length of the bottom of the box as illustrated in dotted lines under the box 11 and are usually such that a substantial space separates each skid. In following out this invention, between or adjacent the skids 14, 25 what I prefer to designate anti-skid plates 15 are placed. These plates may be of any preferred construction but as shown consist of sheets of metal provided with oppositely extending projections 16. The projections 30 16 are formed by forcing a punch through the sheet metal, the punch in passing through the sheet, tearing the metal and causing the projections 16 to be formed which project perpendicularly to the plane of the plate. 35 The punch is first passed through one side of the sheet, causing the projections 16 to project up from the opposite side thereof, and the plate is then turned over and the punch again passed through it, forming projections 16 extending out from the other side of the sheet, thus forming the anti-skid plate 15 which has projections 16 extending outwardly from both sides thereof. The projections 16 are preferably formed with sharp 40 or knife edges so that they will more readily enter the boxes or the floor. When the anti-skid plates 15 are placed between the skids 14 as particularly illustrated in Figures 2 and 5 the distance between the extremity of 45 the projections 16 on one side of the plate and the extremity of the projections 16 on the other side must be substantially greater than the thickness of the skids 14 in order to properly engage both the boxes and the 50 floor 10.

In making up the loads illustrated in the drawings, the anti-skid plates 15 are first placed in proper position on the floor 10 and, referring to Figures 1 and 2, the boxes 11 and 60 12 are placed over them, the anti-skid plates 15 being preferably placed adjacent the edges of the boxes and not near the center where springing of the bottom of the boxes might render them less effective. The weight 65 of the boxes is ordinarily sufficient to cause

the projections 16 to imbed themselves both in the boxes and in the floor 10 to such a degree as to bring the skids 14 into contact with the floor 10, but in case the projections 16 do not imbed themselves to this extent, when 70 the clamp bars 17, 18, and 19 are placed over the boxes as shown and drawn down, the skids 14 are pulled securely into contact with the floor 10 and the projections 16 are forced 75 into the boxes and floor to the proper degree. While it is evident that these plates will work with great efficiency should the skids 14 be eliminated and consequently allow the projections 16 to be imbedded to their full extent, it is considered preferable to use 80 the construction shown, as in the same not only the holding force of the anti-skid plates is realized but also the friction between the skids 14 and floor 10.

After the boxes 11 and 12 are in place, 85 anti-skid plates 15 are placed in proper position on their top surfaces and the box 13 is set in place thereover. When all the boxes are in place the load clamp bars 17, 18 and 19 are placed over the boxes as shown and 90 are pulled down into place by means of the rods 20, whose lower hooked ends engage the stake pockets 21 or other suitable securing means, and whose upper ends project through the ends of the clamp bars 17, 18 and 19 and threadably receive nuts 22 95 thereon.

Although the means for holding the boxes is such, and is intended to be sufficient, to prevent movement of the boxes when the freight car is subjected to ordinary jars or shocks, it is not intended to prevent movement of them when the freight car is subjected to unusually violent jars or shocks, for the reason that if they are allowed to 100 shift or move a slight amount when the freight car is subjected to a violent shock, the strain on the boxes and their contents will be materially lessened. The securing means are such that although the boxes may 105 shift, due to a violent shock, the amount of such shifting will be limited in effect by the movement of the boxes themselves. This is for the reason that when the boxes move, they carry the clamp bars 17, 18 and 19 along 110 with them, the lower ends of the rods remaining in the same position relative to the floor, with the result that the clamp bars 17, 18 and 19 tend to revolve about the lower ends of the rods 20, and when the rods 20 move off of the vertical, the clamp bars tend to move 115 towards the floor, and exert an increasing clamping action on the boxes which in turn increases the friction between the boxes themselves and between the boxes and the floor. It is evident that although the boxes may shift, the shifting movement will be limited and not to such an extent as to free 120 the securing means holding the boxes in position on the floor 10. There will be a tend- 125

ency for the clamp bars to slide along the top of the boxes when the latter shift their position, but it has been found that this does not occur until there is a substantial increased 5 clamping action due to the shifting of the boxes, and it may be considered beneficial in many ways, but if it is desired to prevent the clamp bars from any movement whatever relative to the boxes, blocks such as 23 as 10 are shown placed against each side of the clamp bar 8 in Figure 1 may be secured to the box and thereby prevent the clamp bar from movement relative to the box, or anti-skid plates 15 may be placed under the clamp 15 bar as shown under the clamp bar 19 in Figure 1 and the same result will be achieved.

It will be noted that the securing means illustrated is extremely simple and when compared to the conventional means, is also 20 extremely light in weight, the latter effecting a substantial reduction in dunnage charges over the conventional means. Another great advantage of this invention is that the labor charges incurred in loading 25 and unloading the boxes is greatly reduced over the conventional means. In loading, it is only necessary to drop the anti-skid plates in position on the floor, set the boxes in place over them, and where the boxes are superimposed drop some anti-skid plates on the top 30 of the lower boxes and set the upper box or boxes in place, after which the load clamp bars are placed in position and the clamp rods placed in position and drawn up in 35 place, no nails or spikes being used for securing the boxes in place. The operation of unloading is simpler yet, it only being necessary to remove the nuts 22, or to clip the rods 20 by bolt clippers and remove the 40 boxes.

Although I have shown in Figures 1 and 2 a three box load, it is evident that this invention is equally applicable to loads of one box or more, whether they are single decked 45 or superimposed, or loaded in a variety of different positions. By way of illustration I have shown in Figure 6 a load in which one box 24 is placed directly over another box 25, two load clamp bars 26 being placed over 50 each upper box in this case. When another set of superimposed boxes such as 27 and 28 are provided in the same load they are preferably positioned to abut end to end against the boxes 24 and 25 as shown, thereby helping 55 to prevent movement of the adjacent box when it tends to move in that direction.

Formal changes may be made in the specific embodiment of the invention described without departing from the spirit or substance 60 of the broad invention, the scope of which is commensurate with the appended claims.

What I claim is:—

1. Means for securing boxes to a floor dur-

ing shipment, comprising anti-skid plates 65 positioned between said boxes and said floor to prevent horizontal movement of said boxes, means for preventing vertical movement of said boxes relative to said floor comprising clamp bars overlying said boxes and 70 drawn towards said floor by means of rods anchored adjacent said floor, and blocks secured to said boxes and engaging said clamp bars for preventing relative movement between said clamp bars and said boxes. 75

2. Means for securing superimposed boxes supported on a floor comprising, in combination members provided with oppositely disposed projections positioned between the adjacent faces of said boxes and between 80 said floor and said boxes to prevent horizontal movement of said boxes, and means for preventing vertical movement of said boxes relative to said floor comprising a clamp bar extending transversely of said boxes, a member provided with oppositely disposed projections positioned between the adjacent faces of said box and said clamp bar, and rods extending from said clamp bar to the floor, said rods having U-shaped lower ends 85 and plates connecting the free ends of the rods with the main body thereof to prevent disengagement of the rods with the floor. 90

3. Means for securing a box against movement on a floor comprising, in combination 95 anti-skid plates embedded in the load-carrying surface thereof to prevent longitudinal movement of the box relative to the floor, means to prevent vertical movement of the box relative to the floor comprising a clamp bar extending transversely of the box, rods connecting said clamp bar to the floor, and means secured to the box and engaging said clamp bar on either side thereof serving to cause an increased friction between the box 100 and floor upon shifting of the box. 105

4. Means for securing a box against vertical movement on a floor comprising a clamp bar extending across said box, members provided with oppositely disposed projections positioned between adjacent faces of said box and clamp bar to prevent shifting of said clamp bar relative to said box, and rods connecting the free ends of said clamp bar to the floor to secure said box therebetween. 110

5. Means for securing boxes to a floor during shipment comprising, in combination, anti-skid plates positioned between said boxes and floor, clamping bars extending 115 across said boxes, and means secured to said bars and floor for anchoring said bars thereto, said bars being adapted to shift with said boxes thereby causing an increased clamping action on said boxes. 120

Signed by me at Detroit, Michigan, U. S. A., this 7th day of June, 1924.

RICHARD E. BAUS.
